Inventor.

Lawson B. Bidwell

United States Patent Office.

LAWSON B. BIDWELL, OF HARTFORD, CONNECTICUT.

Letters Patent No. 74,882, dated February 25, 1868.

IMPROVED RAILROAD-CHAIR.

The Schedule referred to in these Letters Patent and making part of the same.

TO ALL WHOM IT MAY CONCERN:

Be it known that I, LAWSON B. BIDWELL, of Hartford, in the county of Hartford, and State of Connecticut, have invented a new and improved Railroad-Chair; and I do hereby declare that the following is a full, clear, and exact description of the same, reference being had to the accompanying drawing, and to the letters of reference marked thereon.

The drawing shows a perspective view of the improved chair resting upon the blocks A and B, which represent the "ties" or other supports for the track.

My invention consists in constructing a bridge-chair, intended to extend from one tie to another, or boiler-plate or other flat rolled iron, having a portion of the sides intermediate between the two ends turned up at right angles to the bottom upon which the rails rest.

In the drawing, C and D are the ends of the chair, which are left flat, and rest upon the ties or supports A and B. E and F are the sides of the chair, which are formed from the portion of the plate turned up. The chair is formed from a rectangular plate, *a b c d*, and the sides E and F are formed from the metal included in the space *e f g h* and *e' f' g' h'*, by heating the plate and drawing out the metal near the ends of the portion turned up at *e f* and *g h*, and *e' f'* and *g' h'*, so as to form curved braces *i e* and *j h*, and *i' e'* and *j' h'*, extending from the flat ends C and D to the sides E and F, giving them the necessary lateral stiffness. The middle portions of the sides E and F remain of the original thickness of the plate. These sides give the improved chair great vertical strength and stiffness. In the end portions C and D of the chair, are punched the spike-holes *l m n o*, for securing the chair and rail to the ties. The spikes can also pass through notches in the rails to prevent motion in the direction of their length. The ends of the rails are intended to meet at the middle, *k*, of the chair, and rest flat on the bottom its whole length, and be held firmly by the sides E and F, to prevent any lateral motion. The distance between the sides E and F is to be of the width of the base of the rail.

By means of the improved chair, the bearing of the joint between the two rails is distributed over the two ties or supports A and B, giving great firmness to the rail, and preventing deflection at the joint, and consequent jar to the train when passing over it.

I do not claim a bridge-chair as such, nor do I claim a bridge-chair having a web or webs extending its whole length; but

What I claim as my invention, and desire to secure by Letters Patent, is—

An improved railroad-chair, constructed of plate iron, with a portion of the sides turned up at right angles to the bottom, in such a manner as to leave the bearing-ends of the same width as the original plate, and to have the turned-up portion curved out to the edges of the bearing-ends, to increase their stiffness, substantially as specified.

LAWSON B. BIDWELL.
